CLAIM

The ornamental design for a rope formed by interlocking stitches for use in jewelry, clothing, accessories, or applied to the surface of articles of manufacture, as shown and described.

DESCRIPTION

FIG. 1 is a perspective view of a rope formed by interlocking stitches for use in jewelry, clothing, accessories, or applied to the surface of articles of manufacture, showing my new design with two filaments.

FIG. 2 is a front view thereof; and,
FIG. 3 is a side view thereof.

1 Claim, 3 Drawing Sheets
